CLAIM

The ornamental design for an instrument and utensil for
medical or laboratory diagnosis as shown and described.

DESCRIPTION

FIG. 1 is a top perspective view of the instrument and utensil
for medical or laboratory diagnosis showing my new design.
FIG. 2 is bottom perspective view thereof.

FIG. 3 is a front view thereof.

FIG. 4 is back view thereof.

FIG. 5 is a side view thereof.

(Continued)

FIG. 6 is a top view thereof; and,
FIG. 7 is a bottom view thereof.

1 Claim, 7 Drawing Sheets
